CLAIM

The ornamental design for a display screen with graphical user interface for controlling machine tools, as shown and described.

DESCRIPTION

FIG. 1 is a front view of a display screen with graphical user interface for controlling machine tools showing our new design;

FIG. 2 is a left side elevational view thereof;

FIG. 3 is a top plan view thereof; and,

FIG. 4 is an enlarged view of the display part thereof.

The broken line showing of the display screen is for the purpose of illustrating portions of the display screen and forms no part of the claimed design.

1 Claim, 4 Drawing Sheets
